UNITED STATES PATENT OFFICE.

PATRICK J. MADDEN, OF CHICAGO, ILLINOIS.

VALVE DEVICE FOR WATER-CLOSETS.

No. 926,887.

Specification of Letters Patent.

Patented July 6, 1909.

Application filed December 21, 1907. Serial No. 407,605.

To all whom it may concern:

Be it known that I, PATRICK J. MADDEN, a citizen of the United States, residing at Chicago, in the county of Cook and State of Illinois, have invented certain new and useful Improvements in Valve Devices for Water-Closets, of which the following is a specification.

The present invention relates to a valve-device of the class shown in U. S. Letters Patent No. 569,559 which were granted to me October 13, 1896 and in which an inlet valve and an outlet valve are arranged to operate reciprocally so that when the outlet valve is seated the inlet valve is unseated, and vice versa.

The present invention has nothing to do with the inlet valve but relates solely to the outlet valve and consists in the features of novelty that are hereinafter described.

In the accompanying drawing, which is made a part of this specification; Figure 1 is a vertical section of a fragment of the rear portion of the bowl of a water-closet and a sectional elevation of a valve-device, embodying the invention. Fig. 2 is a rear elevation of a fragment of the bowl, the valve-device being omitted. Fig. 3 is an elevation of a non-circular nut.

A represents a fragment of a water-closet bowl, made of pottery. In its upper rear portion (or elsewhere if desired) is formed a chamber B having one or more openings for the outlet of water so located as to meet the requirements of the particular type of closet to which the invention is applied. The drawing shows two openings, b, leading from opposite sides of the upper portion of the chamber, for supplying the hollow rim, A', of the bowl, an opening, b', leading downward from the bottom of the chamber for supplying the jet opening (not shown) and one of three openings, b², leading downward from the bottom of a portion of the chamber which projects into the bowl. But, as before intimated, the number or location of these water outlet openings is not material.

The rear wall B' of the chamber is provided with an opening b³ which is circular, save for a radial notch, b⁴, formed in the wall of the opening, which increases, in one diametrical direction, its otherwise uniform diametrical dimensions. The front wall, B², of the cham-

ber has through it an opening, b⁵, which is considerably restricted in size, as compared with the opening b³.

The valve-device has a casing which occupies the chamber and the opening b⁵, and comprises a cylindrical externally threaded rear portion, C, a cylindrical front portion, C', which is closed at its front end, save for an opening through which passes the stem, D, of the outlet valve, E, and struts or bridge pieces, C², connecting the parts C and C', the spaces between the adjacent struts being in fact large ports through the sides of the casing. The front end of the casing carries a sleeve, C³, which surrounds the valve-stem, D, snugly, and which also occupies the opening b⁵ through the front wall B² of the chamber, and an elastic packing ring F is placed around the sleeve, between the inner end of the casing and the inner wall of the chamber, so that when the casing is forced inward a water-tight joint will be formed between the inner end of the casing and the front wall of the chamber.

Surrounding and having engagement with the externally threaded portion C of the casing is a nut G, which is located within the chamber and bears against a shoulder within the chamber, the shoulder, in the instance shown in the drawing being, in fact the inner face of the rear wall of the chamber. The nut is non-circular. As shown in the drawing it has oppositely located flat sides, g, one of which is engaged by a flat surface b⁶ on the interior of the chamber, whereby it is prevented from turning.

H is a second nut, surrounding and having threaded engagement with the rear portion of the casing on the outside of the chamber, and adapted to bear against the rear wall of the chamber through the medium of a packing ring h, whereby a water-tight joint is made between the chamber and casing.

The term "chamber" is herein used to designate the hollow portions of the bowl which contains the valve-device, but I desire to have it understood that any space or cavity adapted to contain the valve-device and having an opening at one end for admitting the valve-device and an opening at the other end for the passage of the stem of the valve is within the scope of the invention, so far as this so-called chamber is concerned.

In assembling the parts thus far described, the parts of the valve-device are first assembled in the valve-casing and properly adjusted. With the bowl resting on its back and the chamber B in vertical position, the nut, G, is inserted through the opening b^3-b^4 , the nut being meanwhile held in the diametrical plane of the notch b^4 and with its flat side or sides vertical. After passing through the opening the nut is brought to bear upon the rear wall, B', with its flat side opposite the flat surface b^6 in the chamber, whereby it is prevented from turning. With the packing ring F in place on the sleeve C³, the casing is slipped through the opening b^3 and nut, G, until its threaded portion C engages the nut. The casing is then screwed through the nut until the sleeve C³ has entered the opening b^5 and the packing ring F is compressed sufficiently to form the desired water-tight joint between the end of the casing and the front wall of the chamber. The nut H is then turned home, compressing the packing ring h and forming a water-tight joint between the casing and the rear wall of the chamber.

The joint between the valve-stem D and the walls of the opening in the end of the casing through which it passes is made tight by an elastic packing I, located within the casing. Said packing has a portion i in the form of a frustum and a portion i' in the form of a radial flange at the base of the frustum, the frustum being provided with an opening through which the valve-stem passes with a snug fit. The frustum tapers to a feather edge so that the pressure of the water surrounding it tends to press it tightly against the valve stem and prevent leakage past it. It is found that such a packing is easily injured unless it is protected and this is particularly true if it is used in the position shown in the drawing because of the repeated blows to which it would be subjected by the valve E. To prevent its being injured, a shield in the form of a complementary hollow metallic frustum J is interposed between it and the valve E the base flange j of the metallic frustum resting upon the base flange of the elastic frustum. The elastic frustum serves also to cushion the stroke of the valve and lessen the noise incident to the operation of the valve. Furthermore, the shield completely covers and conceals the elastic frustum, the opening through the shield being just sufficient to receive the valve stem, so that when the valve is bearing against the hollow frustum, the pressure of the latter upon the elastic frustum serves to compress it and thereby more firmly force it against the stem G. The frusta are loose within the casing so as to be freely movable relatively thereto and partake of the movement of the valve stem which the elastic frustum fits tightly and this has the advantage of practically eliminating relative movement between the frusta

and the valve stem with the result that the wearing of the elastic frustum is practically eliminated.

What I claim as new and desire to secure by Letters Patent is:

1. In a water-closet, a bowl having a chamber provided with an outlet for water, an unthreaded opening through its rear wall for admitting a valve-device, and a restricted opening through its front wall, in combination with a valve-device having a casing occupying the chamber and the opening through its rear wall, and having also a valve-stem extending through the opening through its front wall, a nut surrounding the casing and having threaded engagement therewith, said nut being located within the chamber and adapted to bear against a shoulder therein, and means for preventing the nut from turning, whereby the casing may be screwed through the nut and into the chamber until its forward movement is arrested by the front wall of the chamber and the nut is forced to a firm bearing against the shoulder.

2. In a water-closet, a bowl having a chamber provided with an outlet for water, an unthreaded opening through its rear wall for admitting a valve-device, and a restricted opening through its front wall, in combination with a valve-device having a casing occupying the chamber and the opening through its rear wall, and having also a valve-stem extending through the opening through its front wall, a nut surrounding the casing and having threaded engagement therewith, said nut being located within the chamber and adapted to bear against a shoulder therein, means for preventing the nut from turning, whereby the casing may be screwed through the nut and into the chamber, and means for forming a water-tight joint between the casing and the rear wall of the chamber.

3. In a water-closet, a bowl having a chamber provided with an outlet for water, an unthreaded opening through its rear wall for admitting a valve-device, a restricted opening through its front wall and an unthreaded shoulder, in combination with a valve-device having a casing occupying the chamber and the opening through the rear wall thereof, and having also a valve-stem extending through the opening through the front wall of the chamber, a packing interposed between the casing and the front wall of the chamber, a nut surrounding the casing and having threaded engagement therewith, said nut being located within the chamber and adapted to bear against said shoulder and engaging means on the nut and bowl, respectively for preventing the nut from turning, whereby the casing may be screwed through the nut and into the chamber until the packing aforesaid is compressed to form a water-tight joint.

between the casing and the front wall of the chamber and the nut forced against the shoulder.

4. In a water closet, a bowl having a chamber provided with an outlet for water, an unthreaded opening through its rear wall for admitting a valve-device a restricted opening through its front wall and an internal shoulder, in combination with a valve-device having a casing occupying the chamber and the opening through the rear wall thereof and having also a valve-stem extending through the opening through the front wall thereof, a packing surrounding the opening through said front wall, a nut surrounding the casing and having threaded engagement therewith, said nut being located within the chamber and adapted to bear against said shoulder, engaging-means on the bowl and nut, respectively for preventing the nut from turning, whereby the casing may be screwed through the nut and into the chamber until the packing aforesaid is compressed to form a water-tight joint and the nut is forced 25 against the shoulder, a second nut surrounding the casing and having threaded engagement therewith, said nut being located outside of the chamber, and a packing ring interposed between said nut and the rear 30 wall of the chamber for forming a water tight joint between said rear wall and the casing.

5. In a water closet, a bowl having a chamber provided with an outlet for water, an unthreaded opening through its rear wall for admitting a valve-device, a restricted opening through its front wall, an internal shoulder in combination with a valve-device having a casing occupying the chamber and the opening through its rear wall and having also a valve-stem extending through the opening through its front wall, a nut surrounding the casing and having threaded engagement therewith, said nut being located 40 within the chamber and adapted to bear against said shoulder, and engaging-means on the bowl and nut, respectively for preventing the nut from turning, the minimum dimension of the nut being less than the maximum 45 dimension of the opening through the rear wall of the chamber.

6. In a water closet, a bowl having a chamber provided with an outlet for water, an opening through its rear wall for admitting a valve device, and a restricted opening through its front wall, in combination with a valve-device having a casing occupying the chamber and extending through the opening through its rear wall and having 55 also a valve-stem extending through its front wall, a nut surrounding the casing and having threaded engagement therewith, said nut being located within the chamber and adapted to bear against a shoulder therein, 60 the minimum dimension of the nut being less 65

than the maximum dimension of the opening through said rear wall, means for preventing the nut from turning, and a second nut surrounding the casing and having threaded engagement therewith, the nut last 70 aforesaid being adapted to bear against the outside of the rear wall of the chamber.

7. In a water closet, a bowl having a chamber provided with an outlet for water, an opening through its rear wall for admitting a valve-device, the wall of said opening being notched to increase its radial dimension in one direction, and a restricted opening through its front wall, in combination with a valve-device having a casing 80 occupying the chamber and the opening through the rear wall thereof, and having also a valve-stem extending through an opening through its front wall, a non-circular nut surrounding the casing and having 85 threaded engagement therewith, said nut being located within the chamber and adapted to bear against a shoulder therein, and means within the chamber, engaging the nut for preventing its turning. 90

8. In a water closet, a bowl having a chamber provided with an outlet for water, an opening at one end for admitting a valve-device, and a restricted opening at the opposite end, in combination with a valve-device 95 having a casing occupying said chamber, a sleeve carried by the casing and occupying the restricted opening aforesaid, a valve-stem occupying said sleeve and means for forming a tight joint between the sleeve and 100 the end of the chamber.

9. In a water closet, a bowl having a chamber provided with an outlet for water, an opening at one end for admitting a valve-device and at the opposite end a restricted 105 opening, in combination with a valve-device having a casing occupying said chamber, a sleeve carried by the casing and occupying the restricted opening aforesaid, a valve-stem occupying said sleeve, means for forming 110 a tight joint between the valve-stem and the casing and means for forming a tight joint between the sleeve and the end of the chamber.

10. In a water closet, a bowl having a 115 chamber provided with an outlet for water, an opening at one end for admitting a valve-device, and at the opposite end a restricted opening, in combination with a valve-device having a casing occupying said chamber, a 120 sleeve carried by the casing and occupying the restricted opening aforesaid, means for forming a tight joint between the sleeve and the end of the chamber, a valve-stem occupying said sleeve, and a packing ring surrounding the valve-stem, within the casing, 125 for forming a tight joint between them.

11. In a water closet, a bowl having a chamber provided with an outlet for water, an unthreaded opening at one end for ad- 130

- mitting a valve-device, and a restricted opening at the opposite end, in combination with a valve device, having a casing of less diameter than the unthreaded opening aforesaid and occupying the chamber, an unthreaded sleeve carried by the casing and occupying the restricted opening aforesaid, a valve occupying said sleeve and projecting at one end into the casing and at the other end into the bowl, and means for forcing the casing toward the end of the chamber having said restricted opening for the purpose of forming a tight joint between them.
12. In a water closet, a bowl having a chamber provided with an outlet for water, an unthreaded opening at one end for admitting a valve-device, and a restricted opening at the opposite end, in combination with a valve-device having a casing occupying said chamber, an internal sleeve carried by the casing and occupying the restricted opening aforesaid, a valve-stem occupying said sleeve, a packing surrounding the sleeve between the adjacent ends of the chamber and casing, and means for forcing the casing toward the end of the chamber having said restricted opening, for compressing the packing ring and thereby forming a tight joint between the adjacent ends of the casing and chamber.
13. In a valve device, the combination of a valve casing, a valve within the casing, a stem extending through the end of the casing and carrying the valve, an elastic packing located within the casing fitting the stem between the end of the casing and the valve, said packing having a portion in the form of a frustum and a portion in the form of a flange radiating from the base of the frustum and a metallic shield in the form of a complementary hollow frustum surrounding the stem between the elastic frustum and the valve,

the elastic frustum having a tight fit on the valve stem and being out of contact with the valve casing whereby it is free to partake of the movement of the valve stem without friction.

14. In a valve device, the combination of a valve casing having an opening through its front end, a valve stem passing through said opening, a valve carried by said stem, a spring for forcing the valve from its seat, an elastic packing located within the casing and fitting the valve stem tightly, said packing having a portion in the form of a hollow frustum, and a metallic shield in the form of a complementary hollow frustum surrounding the valve-stem between the elastic frustum and the valve, said shield being free within the casing and adapted to receive the impact of the valve, the elastic packing acting as a cushion.

15. In a valve device, the combination of a valve-casing having an opening through its front end, a valve stem passing through said opening, a valve carried by said stem, a spring forcing the valve from its seat, an elastic packing located within the casing and fitting the valve stem tightly, said packing having a portion in the form of a hollow frustum and a portion in the form of a flange radiating from the base of the frustum, and a metallic shield in the form of a complementary hollow-frustum surrounding the valve-stem between the elastic packing and the valve, said shield being free within the casing and adapted to receive the impact of the valve, said shield having a base flange adapted to bear against the flange of the elastic packing.
